FOREIGN PATENT DOCUMENTS

GB 2381728 5/2003

Primary Examiner — Susan Moon Lee(74) *Attorney, Agent, or Firm* — Head, Johnson & Kachigian, P.C.(57) **CLAIM**

The ornamental design for an elevated pet feeder with round bottom bowls, as shown and described.

DESCRIPTION

FIG. 1 is a perspective view of the elevated pet feeder with round bottom bowls;

FIG. 2 is a front view of the elevated pet feeder with round bottom bowls of FIG. 1, where the back view is identical to the front view;

FIG. 3 is a top view of the elevated pet feeder with round bottom bowls of FIG. 1;

FIG. 4 is a cut away front view of the elevated pet feeder with round bottom bowls of FIG. 1;

FIG. 5 is a bottom view of the elevated pet feeder with round bottom bowls of FIG. 1; and,

FIG. 6 is a side view of the elevated pet feeder with round bottom bowls of FIG. 1, where both side views are identical.
